(57) CLAIM

The ornamental design for an air purifier as shown and described.

DESCRIPTION

The patent or application file contains at least one drawing executed in color. Copies of this patent or patent application publication with color drawings will be provided by the Office upon request and payment of the necessary fee.

FIG. 1 is a front perspective view of an air purifier showing our new design;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an exploded perspective view of an air purifier; and,

FIG. 10 is a bottom perspective view of an air purifier in an alternate configuration with the colored portions of the air purifier showing the lighting turned on.

The broken lines depict portions of the air purifier that form no part of the claimed design.
